UNITED STATES PATENT OFFICE.

JOHN M. LACHLAN, OF NEW YORK, N. Y.

STEAM-BOILER.

SPECIFICATION forming part of Letters Patent No. 414,911, dated November 12, 1889.

Application filed May 8, 1889. Serial No. 310,024. (No model.)

To all whom it may concern:

Be it known that I, JOHN M. LACHLAN, of the city, county, and State of New York, have invented a new and useful Improvement in 5 Steam Boilers and Circulators, of which the following is a full, clear, and exact description.

My invention relates to marine and stationary boilers wherein circulating-pipes are 10 employed in the fire-box and also in the water-space at the bottom of the boiler below the ash-pit; and my invention consists in the construction and combination of parts, as hereinafter described and claimed, whereby 15 reliable and effective circulation is produced and the circulation is placed under easy and quick control of the engineer or fireman.

Reference is to be had to the accompanying drawings, forming a part of this specification, 20 in which similar letters of reference indicate corresponding parts in all the figures.

Figure 1 is a sectional side elevation of a boiler having my invention applied thereto. Fig. 2 is a sectional plan view of the same. 25 Fig. 3 is a perspective view of one of the pipe-couplings. Fig. 4 is a reduced sectional plan view of the same. Fig. 5 is an enlarged view of the valve at the inner end of the stand-pipe.

30 B represents the ordinary boiler-shell; C, the tubes; and D the fire-box, containing the grate-bars E in the usual manner. In the space G are placed the stand-pipes H, which are bent and their upper ends passed through 35 the tube-plate I into the water-space J of the boiler above the tubes. The lower ends of the said stand-pipes are each provided with a coupling K, formed with a single neck k to receive the stand-pipe H. Immediately in 40 line with the neck k is formed the neck k' to receive the central heating or circulating pipe L. At each side of the neck k' is formed a curved branch k² to receive the side heating or circulating pipes M M. The front 45 ends of the said heating or circulating pipes are fitted in a coupling N, having central co-incident necks n n' and curved side branches n² n², and this coupling connects the heating

or circulating pipes with a pipe O, which passes out to the front of the boiler and then 50 inward therethrough, where it is connected to the pipe P, which leads into the water-space J and reaches to a point below the ash-pit D', where the water does not receive the same 55 high degree of heat as at the main body of the boiler. The water from this low-heat space, instead of remaining quiescent to retard the generation of steam, enters the heating and circulating pipes L M, located in the fire-box, and is subjected to a very high 60 degree of heat. This causes a rapid circulation of water from the low-heat space through the pipes O P and couplings N into the heating and circulating pipes L M, thence through the couplings K and stand-pipes H to the 65 water-space either above or below the water-line, as may be deemed desirable in practice. The current from the pipe O to the stand-pipe H, being direct through the central necks k' n' and central pipe L, meets the minimum 70 of resistance or obstruction, which would not be the case if all the water were forced to pass through the two side pipes M and the curved side branches of the couplings.

The upper end of the stand-pipe H is provided with a valve H', constructed to receive a gate h. The passage h' in the valve which receives the gate h is open at the bottom at h², so that clogging of the valve is impossible and there is no interference with its free 80 operation. To the upper end of the gate h is attached the rod h³, which passes through the stuffing-box h⁴, and is connected to one arm of the bell-crank lever h⁵, pivoted in a standard at the top of the boiler. To the 85 other arm of the bell-crank lever is attached the operating-rod h⁶, which reaches to the front of the boiler, where it can be easily reached and instantly operated for closing the cock. In that portion of each of the pipes 90 O at the front of the boiler is fitted a gate-valve O', adapted for instant operation for closing the said pipes.

The pipes P in the space below the ash-pit are each formed with a bell-mouth p, over 95 which wire-cloth p' is placed to prevent clog-

ging, and numerous holes p^3 are formed in the sides of the pipes to admit water to the interior of all the line of the pipe.

Having thus described my invention, what I claim as new, and desire to secure by Letters Patent, is—

The stand-pipe H , entering the boiler, in combination with the valve H' , having open-

ing h^2 and gate h , and the rod h^3 , bell-crank h^5 , and operating-rod h^6 , substantially as described.

JOHN M. LACHLAN.
